UNITED STATES PATENT OFFICE.

ERNEST ODES COX, OF WETUMKA, OKLAHOMA.

LUBRICATING DEVICE.

1,109,402.

Specification of Letters Patent.

Patented Sept. 1, 1914.

Application filed February 27, 1914. Serial No. 821,619.

To all whom it may concern:

Be it known that I, ERNEST O. Cox, a citizen of the United States, residing at Wetumka, in the county of Hughes and State of Oklahoma, have invented certain new and useful Improvements in Lubricating Devices; and I do hereby declare the following to be a full, clear, and exact description of the invention, such as will enable others skilled in the art to which it appertains to make and use the same.

This invention relates to new and useful improvements in lubricating devices, and has for its principal object to provide a lubricator which is capable of use on stationary as well as portable engines and similar machinery.

Another object of this invention is to provide a simple and effective lubricating device by means of which a forced feed of the lubricant is obtained without the necessity of providing any complicated combination of parts to obtain the desired results.

A further object of the invention is to provide a device to which access may be easily and quickly gained so that cleaning of the device may be accomplished without undue inconvenience.

A still further object of the invention is to provide a novel lubricating device which may be used to lubricate a plurality of bearings simultaneously.

With the above and other objects in view the invention consists in the novel combination and arrangement of parts which will be fully set forth in the following specification and accompanying drawings, in which,

Figure 1 is a longitudinal sectional view of a lubricator constructed in accordance with this invention, Fig. 2 is a transverse sectional view taken on line 2-2 of Fig. 1, and showing a plurality of pumps arranged around the main lubricant reservoir in dotted lines.

Referring now to the drawings by characters of reference, the numeral 1 designates generally the lubricant receiving chamber which comprises the cylindrical wall 2 having formed at the lower end thereof the closure 3. Threaded on the upper end of the cylindrical wall 2 is provided the cap 4 having formed therein the centrally located aperture 5. A stem 6 is extended through the aperture 5 as clearly shown in Fig. 1 and is provided at its upper extrem-

ity with the hand hold 7, by means of which the operation of the stem may be controlled.

At the end of the stem 6 opposite the hand hold 7 is provided the oil tight plunger 8 which is slidable within the cylinder 2 and is arranged to force the oil out of the lower end of the cylinder as will be more fully hereinafter described. Threaded into the cylindrical casing 2 and communicating with the interior thereof is provided the nipple 9 having secured to its free end the manually operable valve 10 of any preferred construction. A similar nipple 11 is secured to the opposite terminal of the valve and communicates with the interior of the air pump which will be more fully hereinafter described.

The air pump above referred to, is designated generally by the numeral 12 and comprises the cylindrical casing 13 having formed at its lower end the closure 14. A threaded cap 15 is secured to the upper end of the cylindrical casing and is adapted to form a closure therefor. A centrally located aperture 16 is formed in the cap 15 and is arranged to receive the stem of the plunger which will be more fully hereinafter described.

The plunger above referred to comprises the head 17 which fits tightly within the cylinder 13 and is slidable therein. This head 17 is provided with the stem 18 which extends through the aperture 16 in the cap 15 and terminates at its upper end in the handle portion 19 as clearly shown in Fig. 1.

The lower end of the casing 13 is provided with an aperture in which the nipple 20 is secured which is adapted to provide a connection for the conductor tube 21, by means of which lubricant is conveyed to the part upon which it is desired that the same shall be used. A suitable inwardly opening check valve 22 is located near the bottom of the cylinder 13 and is arranged to admit air to the interior of the cylinder when the plunger is drawn upward.

It is to be understood that in the foregoing description, a single pump is illustrated, but if so desired, a plurality of pumps may be attached to the reservoir 1 as shown in Fig. 2, thus providing for the lubrication of several different bearings simultaneously.

It will be evident from the foregoing that in use, the chamber 1 is filled with any

suitable lubricant which is capable of flowing through the nipple 9 in the bottom thereof. The valve 10 is then opened, and it will be evident that the desired amount of lubricant 5 may be admitted to the pump 12. During the process of admitting the lubricant to the pump, it is essential that the piston in the pump be lowered so that the chamber therein will be relatively small. After closing 10 the valve 10, the pump piston is raised and it will be apparent that the cylinder will fill with air through the means of the air valve 22 and upon forcing the plunger down the valve will automatically close and the 15 lubricant within the chamber will be forced through the nipple 20 and into the conductor pipe 21 by which it is conveyed to the desired bearing.

While in the foregoing there has been 20 shown and described the preferred embodiment of this invention, it is to be understood that such changes may be made in the combination and arrangement of parts as 25 will fall within the spirit and scope of the claims.

Having thus described my invention, I claim:

1. A device of the character described comprising a lubricant receiving chamber, a 30 plunger slidable in said lubricant receiving chamber, means to slide the plunger in the lubricant receiving chamber, a pump, tubular means connecting the lower end of the pump with the lubricant receiving chamber, 35 a piston slidable in the pump, an air valve near the lower end of the pump, said air valve being adapted to admit air to the pump cylinder when the piston is being drawn upward, and a conveyer tube connected to the pump and adapted to carry the lubricant to the desired point.

2. A device of the character described comprising the combination with a cylinder 45 adapted to receive lubricant, a piston slid- able in the cylinder, a duct connected to the lower end of the cylinder, of a pump connected to the end of the duct opposite the

lubricant receiving cylinder, a valve in the duct between the lubricant receiving cylinder and the pump, a piston slidable in the 50 pump, an air valve near the lower end of the pump, said air valve being adapted to admit air to the interior of the pump when the piston is being drawn away from the duct, and means connected to the pump near the 55 duct to carry the lubricant to the desired point.

3. A device of the character described comprising a cylindrical lubricant receiving chamber, a closure at one end of said chamber, a removable closure at the opposite end of said chamber, said removable closure being provided with a centrally located aperture, a plunger slidable within the lubricant receiving chamber, a stem on the plunger, 60 said stem extending through the aperture in the removable closure, a hand hold at the free end of the stem, and a lubricant duct near the closed end of the lubricant receiving chamber, of a valve in the duct and 65 adapted to close the same, a pump at the end of the duct opposite the lubricant receiving chamber, a piston slidable in the pump, a closure formed at the end of the pump, a removable closure secured to the opposite end of the pump, said removable closure being provided with a centrally located aperture, a piston slidable in the 70 pump, a stem on the piston, said stem being adapted to extend through the aperture in the removable closure, handle on the end of the stem by means of which the device is 75 operated, an air valve in the pump cylinder near the lubricant duct, and a conveyer tube communicating with the interior of the 80 pump and adapted to convey the lubricant to the desired point.

In testimony whereof I affix my signature in presence of two witnesses.

ERNEST ODES COX.
